UNITED STATES PATENT OFFICE.

WILLIAM N. SPRINGER, OF SOUTH BEND, INDIANA, ASSIGNOR TO OLIVER CHILLED PLOW WORKS, OF SOUTH BEND, INDIANA.

ENGINE GANG-PLOW.

1,101,350.

Specification of Letters Patent. Patented June 23, 1914.

Original application filed September 17, 1913, Serial No. 790,340. Divided and this application filed December 9, 1913. Serial No. 805,588.

To all whom it may concern:

Be it known that I, WILLIAM N. SPRINGER, of South Bend, in the county of St. Joseph and State of Indiana, have invented certain new and useful Improvements in Engine Gang-Plows; and I do hereby declare the following to be a full, clear, and exact description of the invention, such as will enable others skilled in the art to which it applies to make and use the same.

This invention relates to improvements in engine gang plows and more particularly to mechanism for raising and lowering the plow units,—the same being a division of my application Serial No. 790,340 filed Sept. 17th 1913.

The object of my invention is to provide simple and efficient means for raising the plow units successively.

20 A further object is to provide manually operable means whereby the accurate successive operation of the raising means and their successive release to permit the lowering of the plow units, may be insured.

25 A further object is to so construct raising and lowering mechanism for the plow units of a gang plow, that each plow unit may have such mechanism carried thereby, and so that the manually operable controlling 30 means for the mechanisms on the several plow units, may be mounted upon the truck frame and operatively connected with the raising and lowering mechanisms in such manner as to effect the successive operation 35 of the same.

With these and other objects in view, the invention consists in certain novel features of construction and combinations of parts as hereinafter set forth and pointed out in 40 the claims.

In the accompanying drawings; Figure 1 is a side elevation of a portion of a plow structure embodying my improvements; Fig. 2 is a plan view of the same; Figs. 3, 4, and 5 are 45 views illustrating the cam mechanism for controlling the step-by-step operation of the raising and lowering mechanism; Fig. 6 is an enlarged plan view showing the clutch devices for the raising mechanism; Figs. 7 and 8 are detail views showing the latch devices for the arm 27; Fig. 9 is an enlarged detail view of the arm 27 and the segment 30; Figs. 10, 11 and 12 are detail views of the cam blocks 93—94, Fig. 10 being a sec-

tion on the line 10—10 of Fig. 11; Figs. 13 and 14 are detail views of the levers 74, and Figs. 15 and 16 are enlarged detail views of the arms 79.

1 represents the diagonal rear beam of the truck frame of an engine gang plow and to this beam, brackets 2 are secured, the number of such brackets corresponding to the number of plow units to be employed. In Fig. 2 of the drawing, a single complete plow unit is shown, but it will be understood that a plurality of such units will be comprised in the plow structure. As all of said plow units and the operating mechanism for the same, are duplicates of each other, a detail description of one will suffice for all.

Each plow unit comprises two members 3—4 spaced apart and held rigid with respect to each other by means of a transverse bracket or spacer 5 located intermediate of the ends of said beam members and securely bolted to the latter. The beam member 3 is straight from end to end, while the rear portion of the beam member 4 is bent toward the beam member 3 and lies parallel with the latter, so that the rear portions of the beam members will be properly spaced apart to receive the upper portion of a plow standard 6 and connecting means therefor, said plow standard being secured at its lower end to the soil-engaging member 7. The forward ends of the beam members 3—4 are connected by a bracket 8, and the latter is provided with forwardly projecting arms 9 provided with bosses 10, having pivotal connection with the brackets 2.

At points in rear of the bracket or spreader 5 and in advance of the bent rear portion of the beam member 4, guide brackets 16 are securely bolted to the inner faces of the respective beam members and the guideways 95 of these brackets are slightly inclined forwardly to receive forwardly inclined standards 17. The lower ends of the standards 17 are connected by the axle of a gage or lifting wheel 18, and the upper ends of said standards are connected by a frame or bracket 19, which projects forwardly from the same. Securely bolted to the beam member 4 near the rear end of the latter and projecting above the same, is a bracket 20 provided at its upper forward end with laterally projecting bosses 21^a, to receive bosses 21^b on the two members of a triangu-

lar arm 21 and form pivotal supports for the latter. The two sections of the arm 21 embrace the lower end of a lifting lever 22, which is secured thereto,—said arm 21 thus 5 constituting means whereby the lifting lever is pivotally connected with the bracket 20. The depending portions of the sections of the triangular arms are provided with laterally projecting hubs or bosses 23, to which the 10 upper ends of lifting bars 24 are pivotally connected by means of a bolt 25,—the lower ends of said lifting bars being pivotally connected with arms 26 secured to the lower ends of the standards adjacent to the 15 axle of the gage or lifting wheel 18. It is apparent that if the lever 22 be moved downwardly, the rear ends of the beam and the soil-engaging member will be raised, the guides 16 on the beam members moving upwardly on the standards 17, and that when 20 said lever is raised, the plow beam and soil-engaging member will be lowered.

An arm 27 is pivotally mounted between its ends upon the boss 21^b of one of the sections of arm 21 and in this manner said arm 27 is supported by the bracket 20, with its pivotal support in line with that of the lever arm 21. One end of the arm 27 is made with a head 28 having a recess 29 in one 30 face, and the other end of said arm is made with a toothed segment 30. The head 28 at the smaller end of the segment arm 27 enters a slotted enlargement 31 at the rear end of the bracket 20, and is normally held 35 in said enlargement by means of a latch 32,—the latter being pivotally supported on the bracket 20 at its upper end and adapted to enter the recess 29 in the head 28 of said latch arm. The lower portion of the 40 enlargement 31 is made with a transverse hole 33 for the passage of a bolt 34 attached to the lower end of the latch 32, and a portion of the hole 33 is enlarged for the reception of a spring 35 which bears at one end 45 against a suitable head on the free end of the bolt 34 and thus serves to yieldably hold the latch in place when the head 28 of the segment arm is engaged thereby.

A latch 36 is pivoted at one end to the 50 triangular arm 21 and provided with a suitable tooth which is pressed into engagement with the segment 30, by means of a spring 37, and to the free end of the latch, an operating rod 38 is attached.

55 A spring 39 may be attached at one end to the lifting lever 22 and at the other end to the plow standard or to the rear portion of the beam, to assist in the operation of raising the plow when the lifting lever 22 is depressed.

60 The frame 19 secured to the upper ends of the standards 17, is provided with bearings for a shaft 40, to which a sprocket wheel 41 is secured. A larger sprocket wheel 42 is secured to the hub of the gage or lifting wheel

18 and transmits motion, through the medium of a sprocket chain 43, to the sprocket wheel 41 on the shaft 40. The sprocket 41 is provided with clutch teeth 44 to coöperate with clutch teeth 45 on one end 70 of a drum or hub 46 mounted loosely on the shaft 40. The drum or hub 46, which constitutes the movable member of the clutch, is provided at one end with an annular flange 47, which also forms one flange for a sleeve 48 movable with the drum 46. The sleeve 48 is made with an annular enlargement 49, and at one side of the latter, an annular flange 50 is formed and provided with a cam 51 projecting laterally over the peripheral portion of the annular enlargement 49. The sleeve 48 is recessed for the accommodation of a spring 52, one end of which is seated in said recess and the other end of which bears against the frame 19, said spring 85 tending to force the sleeve and the clutch member carried thereby, into operative relation to the clutch member on the sprocket 41.

A chain 53 is attached at one end to the drum 46 and adapted to wind upon the latter, the other end of said chain being connected with the lifting lever 22, through the medium of a hook 54. The hook 54 is bifurcated so as to embrace the lever 22 and the upper ends of the two arms of the hook 95 are pivotally attached to a link 55, one end of which latter is pivotally attached to an arm 56 secured to the lever 22. An adjusting screw 57 passes through the link 55 (preferably near the free end of the latter) 100 and engages the lever 22, whereby the link 55 may be adjusted to adjust the connection of the chain 53 with said lever.

A plate 58 is secured over the forward end of the frame or bracket 19, and at one end of this plate, one end of an arm 59 is pivotally supported and disposed under the plate 58. Near its free end, the arm 59 carries a roller 60 to coöperate with the annular enlargement 49 and cam 51 of sleeve 48, as herein-after explained. At the other end of the plate 58, one end of a lever 61 is pivotally attached, the other end of said lever projecting laterally beyond the opposite side of the frame 19 and connected with the rear end of the latter through the medium of a spring 62,—the rear end of the frame 19 being provided with a hooked arm 63 to receive said spring. The lever 61 is provided between its ends with an elongated slot 64 for the accommodation of a pin 65 secured to the pivoted arm 59, said pin also passing through an elongated slot 66 (approximately at right angles to the slot 64 in the sleeve 61) 115 in the plate 58.

When the parts are in the position shown in Fig. 6, the roller 60 is in engagement with the side face of the annular enlargement 49 and is holding the clutch members separated. Should the lever 61 be moved 120

forwardly, the pivoted arm 59 with which said lever is connected, would also be moved forwardly and the roller 60 moved out of engagement with the side of enlargement 49, such movement of the pivoted arm and 5 roller being guided and limited by the movements of the pin 65 in the elongated slots 64 and 66. When the roller 60 shall have been moved as above described, the sleeve 10 48 will be free to be slid on the shaft 40 by the action of the spring 52 for engaging the clutch teeth 45 with the clutch teeth 44. In other words,—the spring 52 will be free to 15 act in moving the sleeve 48 to close the clutch. Motion will now be imparted to the drum 46 to wind the chain 53 thereon for effecting the lowering of the lifting lever 22 and the consequent raising of the plow beam and soil-engaging member. At this time, 20 however, the lever 22 will be locked to the segment arm 27 and the latter will be released from the spring pressed latch 32 in the slotted enlargement 31, and move with 25 said lever.

When the lifting lever 22 shall have been depressed to raise the plow as hereinbefore described by the application of power from the wheel 18, it will be held in such position by the engagement of a hook 67 with a bolt 30 68 on the lever 22. The hook 67 is pivotally mounted upon a pedestal 69 located on the spreader 5 and is limited in one direction by a foot 70. A lug 71 projects forwardly from the hook and between this lug 35 and a support on the pedestal, a spring 72 is disposed to retain the hook in and return it to its normal position. The hook 67 is bifurcated to embrace the lever 22 when the latter is lowered, and the members of said hook are provided at their upper ends with beveled or cam projections 73 to engage the bolt 68 on the lever and cause the hook to 40 snap over the same.

As hereinbefore stated, each plow unit is 45 provided with the lifting devices such as above described in detail, and devices which will now be described, are provided for causing the mechanisms on the several plow units to be operated successively to effect the 50 raising of the plows one after another or to drop them in succession.

In line with each plow unit, two levers 55 74—75 are pivotally supported at or near one end by a bracket 76 secured upon the beam 1 of the truck frame. The lever 75 is connected by means of an adjustable rod 77 with the free end of the clutch lever 61, and the lever 74 is connected by means of an adjustable rod 78 with the hook 67. 60 Each lever has pivotally attached thereto, an arm 79 carrying a roller 80 at its free end, and each of said arms is provided at its pivoted end with a projection 81 (disposed at right angles to said arm) and provided 65 with an opening 82. A screw 83 (having a

head at its rear end) passes forwardly through the opening 82 and through a hole in a flange 85 on the lever (74 or 75). The screw 83 is provided with a nut 86 between which and the flange 85 of the lever (74 or 75), a spring 87 is located. A bar 88 is mounted to slide through the brackets 76 on the truck frame and with this bar, a rack 90 is connected and adapted to receive motion from a pinion 91 on a shaft 92 to be 70 operated manually for imparting motion to the slide bar 88. Opposite each plow unit, two cam blocks 93—94 are secured to the slide bar 88,—the cam block 93 being in position to coöperate with the roller 80 on the 75 arm 79 of lever 74 and the cam block 94 being in position on the slide bar to coöperate with the roller on the arm 79 of lever 75, and the several pairs of cam blocks on the slide bar are so disposed that they will, 80 normally, be different distances from the levers 74—75 which they are intended to actuate, so that when the slide bar is moved, the levers 74—75 connected with the respective plow units will be operated successively 85 for the purpose of causing the plows to be raised or dropped in succession, according to the direction in which the slide bar is moved.

The cam blocks 93—94 of the several 90 pairs, are the same in construction but are oppositely disposed on the slide bar 88. Each cam block is constructed with an upwardly inclined face 95 to receive roller 80 and cause the operation of lever 74 or 75 100 when the slide bar 88 is moved in one direction, and each cam block is also made with a transversely beveled rear wall 96 to receive roller 80 and cause the arm 79 which carries it, to swing out of the path of said 105 cam block and pass it without actuating the lever (74 or 75 as the case may be) when the slide bar is moved in the reverse direction.

Let it be assumed that all the plows are 110 in working position, with the mechanism of each plow unit disposed as shown in Figs. 1 and 2, and that it is desired to raise the plows successively. The operator will move the slide bar longitudinally and cause the mechanism of each plow unit to be operated 115 in succession. As a cam block 94 engages the roller 80 on the arm 79 of a lever 75, the latter will be turned on its fulcrum and motion will thus be imparted through rod 77 to the clutch lever 61 of a plow unit,—the 120 movement of said clutch lever acting to withdraw the roller 60 from the annular enlargement 49 and release the movable clutch member and permit the teeth 45 to engage the clutch teeth 44 on sprocket wheel 125 41. The chain 53 will be wound upon the drum 46 by power from the wheel 18, as hereinbefore explained, and the lever 22 will be lowered to raise the plow. When the plow shall have been thus raised, the lever 130

22 will be retained in its lowered position by the hooks 67, and the clutch will be automatically opened by the coöperation of the cam 51 with the roller 60 and said roller will be forced in front of the annular enlargement 49 by the action of the spring 62.

When it is desired to release the levers 22 to permit the plows to drop to working positions, the operator will move the slide bar 88 in the reverse direction, whereupon the cams 93 will operate the levers 74 of the several plow units successively, and thus cause motion to be imparted through the rods 78 to the hooks 67 to withdraw the same from engagement with the levers 22, permitting the latter to rise and the plows to drop to working position. When the plow drops to working position, the segment arm 29 will become automatically locked in its normal position by the action of the latch 32.

Various changes might be made in the details of construction of my invention without departing from the spirit thereof or limiting its scope and hence I do not wish to restrict myself to the precise details herein set forth.

Having fully described my invention what I claim as new and desire to secure by Letters-Patent, is:—

30 1. In a gang plow, the combination with a truck frame and plow units pivotally connected therewith, of raising mechanism carried by each plow unit, means on the truck frame and connected with the raising mechanism for controlling the operation of the same, a latch device on each plow unit for retaining the same elevated, and means on the truck frame and connected with said latch device for operating the same to drop the plow unit.

40 2. In a gang plow, the combination with a truck frame and a plurality of plow units, of raising mechanism carried by each plow unit, controlling devices on the truck frame connected with the raising mechanism of the several plow units, and means on the truck frame operatively associated with the several controlling devices for operating the same successively to effect the raising of the plow units one after another.

50 3. In a gang plow, the combination with a truck frame and a plurality of plow units, of raising mechanism carried by each plow unit, a latch device for each raising mechanism, devices on the truck frame for controlling the raising mechanisms of the several plow units successively, and means on the truck frame for operating the latches of the several raising mechanisms successively to drop the plow units.

60 4. In a gang plow, the combination with a truck frame and a plurality of plow units connected therewith, of power driven raising mechanism carried by each plow unit, each of said mechanisms including a clutch

and means for controlling the same, levers mounted on the truck frame, connections between said levers and the clutch controlling means of the raising mechanisms, and means for operating said levers successively. 70

5. In a gang plow, the combination with a truck frame and a plurality of plow units connected therewith, of power driven raising mechanism carried by each plow unit, each of said mechanisms including a clutch 75 and means for controlling the same, levers mounted on the truck frame, connections between said levers and the clutch controlling means of the raising mechanisms, a slide bar mounted on the truck frame, means for sliding said bar, and cams secured to said bar, said cams being disposed to operate said levers in succession to effect the successive raising of the plow units. 80

6. In a gang plow, the combination with 85 a truck frame, and a plurality of plow units connected therewith, of raising mechanism carried by each plow unit, means on the truck frame for controlling the operation of said raising mechanisms successively, latch 90 devices on the plow units for retaining the plow units in raised position, levers on the truck frame, connections between said levers and latch devices, and means for operating said levers in succession to actuate 95 the latch devices and drop the plow units successively.

7. In a gang plow, the combination with a truck frame, and a plurality of plow units connected therewith, of raising mechanism 100 carried by each plow unit, a latch device on each plow unit for retaining the same in elevated position, a slide bar on the truck frame, means of operating said bar, a pair of levers connected with the truck frame 105 adjacent to each plow unit, connections between one lever of each pair and the raising mechanism on the adjacent plow unit for controlling said mechanism, a connection between the other lever of each pair and the 110 latch device on the adjacent plow unit, and pairs of cam blocks on the slide bar for operating the respective levers, said cam blocks being so disposed that when the bar is moved in one direction one lever of each pair will 115 be operated in succession and so that when the bar is moved in the other direction, the other lever of each pair will be operated in succession.

8. In a gang plow, the combination with 120 a truck frame, and a plow unit connected therewith, of raising mechanism carried by said plow unit, a lever pivotally connected with the truck frame, a connection between said lever and the raising mechanism for 125 controlling the operation of the latter, an arm pivotally connected with said lever, a roller mounted in said arm, a slide bar on the truck frame, a cam block on the truck frame, said cam block having an inclined 130

face to engage the roller and move the lever, said cam block also having a beveled rear wall to engage the roller and move the roller and pivoted arm out of the path of the cam block, and a spring interposed between said pivoted arm and the lever.

In testimony whereof, I have signed this

specification in the presence of two subscribing witnesses.

WILLIAM N. SPRINGER.
